UNITED STATES PATENT OFFICE

RAY B. LAW AND JOSEPHUS A. CLAPPER, OF MUSCATINE, IOWA

SPRING COMPRESSOR

Application filed December 16, 1927. Serial No. 240,470.

This invention relates to a device for compressing springs and, while the same is designed primarily for use in releasing pins and similar structures used in connection with valve stems of automobile engines, it will be understood that the same is useful for other purposes as well and it is therefore not intended to be restricted to any specific use.

10 Among the objects of this invention are to make a more easily operable device of the character indicated; to provide a device which will automatically lock the parts in any desired position; to provide a device of 15 the character indicated which can easily be unlocked and released for movement in a direction opposite to the compressing movement; to provide a device of the character indicated which can not lock in completely 20 actuated position so as to be incapable of being unlocked; to provide a simple easily adjustable device capable of being used upon any style of automobile, regardless of the 25 natural obstructions which may exist within the hood of the car; and such further objects, advantages and capabilities as will hereafter appear and as are inherent in the construction disclosed herein. Our invention further resides in the combination, construction 30 and arrangement of parts illustrated in the accompanying drawing and, while we have shown therein what is now considered the preferred form of our device and a modification thereof, we desire it understood that 35 various modifications are contemplated and are believed to be within the scope of this invention.

In the drawing annexed hereto and forming a part hereof Fig. 1 is a view in elevation of one form of our construction, with a portion of an engine, valve, and spring shown in dotted outline; Fig. 2 is a fragmentary view showing operative elements in a different position; Fig. 3 is a transverse 45 section taken substantially along the plane shown by the broken line 3—3, Fig. 1; Fig. 4 is a transverse view taken thru the lower right hand portion of Fig. 1 to show the internal form of the head for engaging the 50 spring cup used in connection with the coil

spring for seating an engine valve; Figs. 5 and 6 are, respectively, end and side views of a different style of operating cam from that shown in Figs. 1, 2 and 3; Fig. 7 is a fragmentary view showing a modified form 55 of spring for actuating the operating lever.

Referring more in detail to this drawing, the numeral 1 denotes a body member having a split head 2 to straddle the valve stem 3 and engage underneath the valve spring cup 4 to compress the valve spring S and lift the cup out of the way and permit the pin 5 to be removed from the shank or stem 3 of the valve 6. Inasmuch as some automobiles have different spring cup retaining means than a pin, such as a U shaped yoke which is slipped into a groove in the valve stem or a split washer applied in a similar way, we shall, in the appended claims, refer to this as a 60 spring cup retaining means. The head 2 may be secured to the body 1 by any suitable detachable means 7 or may be formed integral therewith or permanently secured thereto, if desired. We prefer to attach this head 65 detachably to the body member and therefore show bolts for this purpose. It is preferred to have the jaws of the head adjustable toward and from each other by means of a bolt and wing nut 8, the purpose being to adjust the jaws 9 of the head to fit different sizes 70 of spring cup 4. Any suitable handle H may be provided on the body member 1, the same being shown in the present instance as a projection extending directly outwardly in the plane of the tool. In one form of our 75 construction this handle is a loop formed integral with the body member 1 and extending in the plane thereof, its two ends being continuous with the body member 1 and the handle being in the form of a loop to furnish a handhold for easily handling the tool in operation. Any suitable handle may be provided.

A bracket arm 10 has slideable connection with the body 1 and is secured in vertically 80 adjusted position thereon by means of the set screw 11, provided with a wing nut or any equivalent device. The bracket 10 is made adjustable in order that this device 85 may be used in connection with springs of 90

- different lengths or valves having stems of different lengths. A lever 12 is pivoted at 13 on the arm or bracket 10 and is actuated around its pivot in one direction by means of the spring 14. Two different types of springs are shown in Figs. 1 and 7, the spring 14^a shown in Fig. 7, being preferred because cheaper to make and install than that shown in Fig. 1. It is also just as efficient as the spring 14. The short end of this lever is provided with a geared sector 15 which engages the teeth of the gear 16 rotatably mounted upon the bracket 10 by the pin 17, which may be screw-threaded or secured in any other convenient manner to the bracket arm 10.
- The arm 10 is provided at its free end with a hollow head 18 thru which slides the plunger 19 pointed at its lower end, as indicated at 20, to engage the valve 6 as shown in Fig. 1.
- This plunger 19 is provided with gear teeth 21 which are engaged by the gear 16 for the purpose of actuating the plunger. The head 18 has a wedge-shaped opening 22 therein for the reception of springs 23 which engage a cylindrical locking member 24 and force the same upwardly. The locking member or roller 24 engages the plunger 25 and forces the same upwardly so as to permit the roller to become wedged between the faces of the head 18 and plunger 19, defining the wedge-shaped channel, to thereby lock the plunger 19 in any adjusted position. Between the plunger 25 and a cooperating plunger 26 is a spring 27 which transmits motion from one to the other of the two plungers and allows relative movement between those plungers when necessary.
- A rotatable eccentric cam 28 operated by means of a handle 29 serves to move the plunger 26 downwardly in the head 18 or to permit it to rise therein a certain amount. In Figs. 5 and 6 is shown a modified form of cam designated by numeral 28^a, the same being provided with a handle 29^a which it is preferred to form integral with the cam. This construction is preferred to that shown in Figs. 1, 2 and 3. The balance between the springs 23 and 27 is such that, when the crank 29 is turned to permit the plunger 26 to rise, the plunger 25 will also be permitted to rise and the roller 24 will engage the relatively inclined surfaces and lock the plunger 19 in position. On the other hand, when the crank 29 or 29^a is turned thru 180 degrees, the plunger 26 will be shoved downwardly, increasing the tension on the spring 27 and thereby overcoming the resistance of the springs 23, thus removing the roller 24 out of locking position, as soon as the same is released by actuation of the handle. A small notch 30 is provided in the edge of the plunger 19 to permit the device to be unlocked when the plunger 19 is fully extended in operation.
- It has been found in actual practice that

without this notch there was a tendency for the roller to become so thoroughly wedged between the relatively inclined faces that it was impossible to release the same from locked position when the cam 28 was turned about its axis. However, the notch 30 entirely eliminates this, the notch being so placed that the handle can be moved downwardly slightly for unlocking purposes, when the cam is turned. Stops 31 are provided on the head 18 to limit the turning movement of the cam 28 or 28^a.

Various modifications within the scope of this invention are possible. For example the tapering compartment 22 may be formed entirely in the head 18 or the compressing member 19 or partly in each. The notch or depression 30 may be formed in the head 18 or in one of the faces of the plunger 19.

While we have disclosed what is now considered the preferred form of construction of this device and certain modifications thereof, it is of course understood that the specific description of structure set forth above may be departed from without departing from the spirit of this invention as set forth in this specification and the appended claims.

Having now described our invention,

We claim:

1. In a spring compressor of the character specified, a frame to engage the spring to be compressed and an element having teeth thereon and movable with respect to the frame to cause compression of the spring; operating means to actuate the movable element, comprising a gear pivotally mounted upon the frame and having its teeth in mesh with the teeth on said movable element, a lever pivoted on the frame and carrying at one end a segmental gear to engage the aforesaid gear, and resilient means to normally withdraw the movable element and retain the parts in position ready for use.

2. In a spring compressor of the character indicated, a supporting arm, a hollow head thereon, a plunger slideable therein, said plunger having gear teeth for engagement by a toothed actuating member, an actuating member on the arm transmitting actuating force to said plunger, means engaging the plunger to lock it in position to hold a spring compressed, and resilient means tending to withdraw the plunger to inoperative position.

3. In a spring compressor of the character indicated, a supporting arm, a hollow head thereon, a slideable plunger movable with relation thereto, means within the head for locking the plunger against spring compression releasing movement, and means partly within the head to render the locking means ineffective.

4. In a spring compressor, a supporting frame, an open head on the frame, a toothed plunger slideable thru the opening in the

head, a spring pressed locking element in the opening to engage and lock the plunger in a forwardly actuated position, and means to release the locking means from holding position.

5. A spring compressor including a head supporting arm, a head on said arm having a hole extending therethru, a toothed reciprocable member movable thru the hole, a locking member in the hole adapted to lock the toothed member in any desired position of adjustment, opposing springs acting upon said locking member biasing it in opposite directions, and adjustable means for determining the normal position of rest under the combined influence of said springs.

6. In a spring compressor, a head carrying a longitudinally reciprocable compressing member, means for actuating said member, and means for locking said member against movement in one direction or permitting it to move when desired, said locking means including a rolling member traveling in a tapering opening in the head, in contact with the compressing member, and resilient means tending to force the rolling member into locking position.

7. In a spring compressor, a head carrying a longitudinally reciprocable compressing member, means for actuating said member, and means for locking said member against movement in one direction or permitting it to move when desired, said locking means including a rolling member traveling in a tapering opening in the head, in contact with the compressing member, and resilient means biasing the rolling member in opposite directions toward locking and unlocking positions.

40 8. In a spring compressor, a head carrying a longitudinally reciprocable compressing member, means for actuating said member, means for locking said member against movement in one direction or permitting it to move when desired, said locking means including a rolling member traveling in a tapering opening in the head, in contact with the compressing member, resilient means biasing the rolling member in opposite directions toward locking and unlocking positions and means for increasing or decreasing the compression of the resilient means.

45 9. In a spring compressor, a head carrying a longitudinally reciprocable compressing member, means for actuating said member, means for locking said member against movement in one direction or permitting it to move when desired, said locking means including a rolling member traveling in a tapering opening in the head, in contact with the compressing member, resilient means biasing the rolling member in opposite directions toward locking and unlocking positions and means for increasing or decreasing the compression of the resilient means,

said device being provided with a depression to permit unlocking thereof when in a fully actuated position.

10. In a spring compressor, a head carrying a longitudinally reciprocable compressing member, means for actuating said member, means for locking said member against movement in one direction or permitting it to move when desired, said locking means including a rolling member traveling in a tapering opening in the head, in contact with the compressing member, resilient means biasing the rolling member in opposite directions toward locking and unlocking positions and means for increasing or decreasing the compression of the resilient means, said compressing member having a depression in the face engaged by the rolling member approximately at the point where said rolling member will be when complete compressing actuation has taken place.

11. In a spring compressor, a head carrying a longitudinally reciprocable compressing member, means for actuating said member, means for locking said member against movement in one direction or permitting it to move when desired, said locking means including a rolling member traveling in a tapering opening in the head, in contact with the compressing member and eccentric means for releasing the locking means.

12. In a spring compressor, a head carrying a longitudinally reciprocable compressing member, means for actuating said member, means for locking said member against movement in one direction or permitting it to move when desired, said locking means including a rolling member traveling in a tapering opening in the head, in contact with the compressing member, resilient means biasing the rolling member in opposite directions toward locking and unlocking positions and cam means for increasing or decreasing the compression of the resilient means.

13. In a spring compressor, a head carrying a longitudinally reciprocable compressing member, means for actuating said member having gear teeth along one face and a depression in another face, means cooperating with the gear teeth to reciprocate the compressing member, the face of the compressing member having the depression and the adjacent face of the head cooperating to define a tapered aperture, a substantially cylindrical locking member in said aperture, resilient means to cause movement of the locking member, and means to predetermine whether said locking member shall or shall not serve to retain the compressing member in actuated position.

14. In a spring compressor for use in removing the spring cup retaining means of an automobile engine, a frame having arms extending at an angle to each other, one of the arms having an opening in the end thereof

to engage the spring cup, the other arm having a bracket adjustably mounted thereon for longitudinal movement thereof, said bracket having at its free end an aperture 5 extending transversely thereof toward the opening in the end of the arm, a reciprocable member in the aperture movable toward and away from said arm, spring actuated locking means in the bracket to engage the reciprocable member in its movement thru the bracket and prevent it from being withdrawn from actuated position, said locking means being capable of being actuated to permit the reciprocable member to move without restraint 10 in either direction, means to actuate the reciprocable member in either direction, and means whereby the spring actuated locking means may be caused to be biased toward locking or unlocking position.

20 In witness whereof, we hereunto subscribe our names to this specification.
